ENTRANCE STAIRCASE FOR MOBILE HOMES
AND THE LIKE

Francis L. Struben, Baltimore County, Md., assignor to Silver Top Manufacturing Co., Inc., White Marsh, Md., a corporation of Maryland

Filed Mar. 10, 1964, Ser. No. 78,945

Term of patent 14 years

(Cl. D13—7)

FIG. 3.

FIG. 2.

FIG. 4.

FIG. 5.

FIG. 6.

FIG. 1 is a perspective view of a novel entrance staircase for mobile homes and the like incorporating my new design;

FIG. 2 is a front elevation thereof;

FIG. 3 is a right side elevation thereof;

FIG. 4 is a plan view thereof;

FIG. 5 is a bottom plan thereof; and

FIG. 6 is a section taken along lines 6—6 of FIG. 2.

I claim:

The ornamental design of an entrance staircase for mobile homes and the like, as shown.
